UNITED STATES PATENT OFFICE.

HARRY PECKER, OF LYNN, MASSACHUSETTS.

KEY HOLDER.

Application filed February 29, 1928. Serial No. 257,870.

My present invention, in its broad aspect, has to do with improvements in combined key purses or holders, and identification means in conjunction therewith; and more particularly it is my purpose to provide a unique and novel means for retaining keys, and the like in a folder or purse, and which has in conjunction therewith means for mounting and retaining an identification card, or the like. My device, furthermore, is a one-piece sheet metal attachment which may be cheaply and readily manufactured in quantities, and its simplicity is its most important characteristic. My device may be used either with an endless key retaining chain or with that type of key retaining chain which has free ends and which is adapted to be suspended by those ends from my attachment, and to securely hold those ends in place I provide novel locking means in the form of a spring catch for engaging the ends of the key chain. My combined structure furthermore requires the use of but a single sheet of leather which serves as a folder or purse for the keys, and the identification means (such as a card or the like) is securely retained against displacement both by the peculiar formation of my novel attachment and the key chain itself which serves as an additional stop against accidental loss of the identification card. Broadly stated, my attachment comprises a piece of sheet metal stamped and bent to provide a retaining frame for identification means and a chain catch thereabove through which the key chain is trained and retained. Other and equally important objects will be apparent from the following detailed description of the various parts of my key holder, and upon inspection of the drawing showing the principal embodiment of my key holder, and wherein;

Figure 1 is a perspective view of my complete device opened up;

Figure 2 is a perspective view of my key holding and identification attachment,

Figure 3 is a back view of my attachment, and

Figure 4 is a detail sectional view of my attachment and shows the novel means of retaining the ends of a key chain of the type which has free ends (as distinguished from an endless key chain).

In the drawings wherein like characters of reference are used to designate like or simi-

lar parts throughout the several views;—

The numeral (1) designates the one piece leather back of my device which is folded at (2) and (3) to provide closing flaps with suitable fasteners (4) and (5). My attachment is a one-piece sheet metal stamping having a body portion (6) which is secured to the leather back (1) as at (7), and which has bent over flanges (8) forming a pocketing frame for an identification card (9), and over which may be placed a suitable celluloid or other transparent cover (10). The cover and card are simply slipped into the frame as shown in Figures 1 and 2. An extension (11) or offset portion is formed on the top edge of the body portion (6), is curved forward and back as at (12), and has openings (13) therein through which an endless key chain (14) is adapted to be trained and secured, as shown in Figure 1. The extension (11) is bent slightly forward as shown at (15), and as above noted, so that it forms an obstruction against withdrawal of the identification card, and in this connection it is to be noted that the key chain itself also serves as a secondary stop against accidental loss of the identification card.

When the chain of the type which is not endless is used, the ends (16) thereof are inserted in the openings (13) and a spring latch or clip (17) having bifurcated ends (18) is disposed to engage the ends of the chain as shown in Figures 3 and 4 so that the chain cannot become detached or the like. Dislodgement of the spring catch is prevented since it must be bowed out, as shown in dotted lines in Figure 4, to remove it, and this is prevented by the leather back (1) unless the back is intentionally bent back so as that the spring may be grasped, bowed, and released.

In operation, the key (19) or keys are placed on the chain and the same inserted in the openings (13), the identification card (9) and its cover (10) having first been inserted in the pocket or frame therefor. The key or keys hang down but do not interfere with inspection of the identification card, and may be handily used when required. From the standpoint of usefulness and simplicity, as well as the unique arrangement of the several elements, it is believed that my device represents a substantial step forward in the art.

While in the foregoing there has been

illustrated in the drawings and described in the specification such combination and arrangement of elements as constitute the preferred embodiments of my invention, it is nevertheless again desired to emphasize the fact that interpretation of the invention should only be conclusive when made in the light of the subjoined claims.

I claim:—

- 10 1. In a key holder, the combination of a body portion having an extension thereon from which keys are suspended, said extension having spaced openings therein, a length of key retaining chain, the end links of which extend through the openings to the back of the extension, and a spring member between the openings in the back of the extension and the ends of which engage about the end links of the chain to force same into engagement with parts of the walls of the openings thereby to retain the chain in position.
- 15 2. In a key holder, the combination of a body portion having an extension thereon

from which keys are suspended, said extension having spaced openings therein, a 25 length of key retaining chain the end links of which extend through the openings to the back of the extension, and an elongated plate spring between the openings in back of the extension and the ends of which are 30 bifurcated to extend beyond the openings thereby to engage about the end links of the chain to force same into engagement with parts of the walls of the openings thereby to retain the chain in position.

35 3. In a key case, a plate having label holding means and an offset portion resisting withdrawal of a label therefrom, a chain for attaching keys thereto, and said chain being so arranged with respect to said plate that 40 when the same is in operative position it also acts as a further stop to prevent withdrawal of a label from the label holder.

In testimony whereof, I affix my signature hereunto.

HARRY PECKER.
